UNITED STATES PATENT OFFICE

124,617

DESIGN FOR A LUMINAIRE FOR USE WITH TUBULAR FLUORESCENT LAMPS

William J. Strassburger and Verne W. Hunter,
Pittsburgh, Pa., assignors to Grant Building,
Incorporated, Pittsburgh, Pa., a corporation of
Pennsylvania

Application November 12, 1940, Serial No. 96,502

Term of patent 14 years

To all whom it may concern:

Be it known that we, William J. Strassburger and Verne W. Hunter, citizens of the United States and residing at Pittsburgh, in the county of Allegheny and State of Pennsylvania, U. S. A., have invented a new, original, and ornamental Design for a Luminaires for Use With Tubular Fluorescent Lamps, of which the following is a specification, reference being had to the accompanying drawing, forming a part thereof, wherein:

Figure 1 is a perspective view; and

Figure 2 is an end view of a luminaire for use with tubular fluorescent lamps embodying our new design.

We claim:

The ornamental design for a luminaire for use with tubular fluorescent lamps, as shown.

WILLIAM J. STRASSBURGER.
VERNE W. HUNTER.
